United States Patent Office

Des. 188,433
Patented July 19, 1960

188,433

TEA BAG SQUEEZER

Nick C. Nikitas, 9 Bentley St., Salem, Mass.

Filed Mar. 7, 1960, Ser. No. 59,650

Term of patent 14 years

(Cl. D44—29)

Fig. 1.

Fig. 2.

Fig. 1 is a front view of the tea bag squeezer embodying my design; and

Fig. 2 is a side view of the tea bag squeezer.

The rear view of the tea bag squeezer is the same as the front view.

I claim:

The ornamental design for a tea bag squeezer, substantially as shown and described.
